UNITED STATES PATENT OFFICE

OLIVER T. FRANCIS, OF QUANTICO, VIRGINIA

RADIO

Application filed December 17, 1928. Serial No. 326,658.

This invention relates to regulators of electric current and potential, and more particularly to the regulation of differences of potential between the elements of a vacuum tube 6 amplifier.

One object of the invention is to automatically control the output of a vacuum tube amplifier in such a manner as to cause it to discriminate against input energy of a value 10 above or below a predetermined value, causing said input energy not to appear in the output circuit, or to be of greater value than the input energy of the desired value. Another object is to cause extremely loud signals 15 such as crashes of static to be eliminated from the output circuit of said amplifier and signals which ordinarily cause blasting in the ordinary receiver to be no louder than signals of less magnitude impressed on said amplifier. Another object is to provide an automatically 20 variable grid leak which shall keep the static grid potential of a vacuum tube amplifier at a constant value regardless of the strength of the incoming signal. Another 25 object is to provide a circuit in the output circuit of a vacuum tube amplifier in which virtually no current shall flow until a certain predetermined voltage is impressed on the grid of same at which time a considerable 30 amount of current shall flow in said circuit.

A still further object is to place the present means of manual control of vacuum tube amplifiers under automatic control by means 35 of regulating the impedances across the input or output thereof, and of regulating the heat of the filament thereof.

With these and other objects in view the invention may be more fully understood by reference to the following description in connection 40 with the drawing which shows diagrammatically several of the embodiments of the invention.

Figure 1 shows a single stage amplifier employing in accordance with the invention a variable impedance element as grid leak.

Fig. 2 shows a means of varying the impedance of the element inversely in accordance with the envelope of the strength of the 50 incoming signal.

Fig. 3 illustrates how the principles involved may be utilized to control the heat of the filament of the amplifier.

Referring to Fig. 1, we find the vacuum tube V_1 coupled to the previous stage of 55 amplification V by means of R_1 . Instead of a grid leak of the ordinary type the primary P_1 of a transformer L_1 has been used. In the secondary S_1 of this transformer has been inserted a variable resistance N_1 , which has 60 the characteristic of possessing a very high resistance until a certain voltage is impressed thereon at which time it has a very small resistance. Such a resistance is a Geissler tube, 65 a neon lamp, a voltage regulator tube, a small spark gap. The primary of this transformer, which in the present instance is a step up transformer has a high impedance to alternating current impressed on the grid of V_1 . If due to a strong incoming signal the grid of 70 V_1 would tend to become negative as is the case with ordinary grid leaks with resistance coupled amplifiers when a strong signal is received, the impedance of L_1 would become small, since the voltage induced in the secondary of this transformer would break down the resistance of N_1 . Thus we find that the 75 grid of this tube is maintained at a constant static potential with respect to the filament and modulation which occurs with resistance 80 or impedance coupled amplifiers is impossible. In the case of transformer coupled amplifiers it is obvious that the resistance N_1 could be placed directly between the grid and filament with similar results.

Fig. 2 shows a method of varying the impedance of the grid leak of V^2 inversely in accordance with the envelope of the strength of the incoming signal, impressed upon the primary P^5 of transformer L^5 . The primary P^2 of the transformer L^2 is here performing the function of a variable grid leak. In the secondary S^2 of the transformer is inserted an element N^2 . In parallel with N^2 is the element R^2 which is a high fixed resistance. The tube V^3 is coupled to the previous stage of amplification. On the grid of V^3 is impressed a sufficiently great negative voltage so that very little current will flow in the output circuit of this tube when ordinary 10

signals are being received. This small current will not cause an IR drop across R^3 sufficiently great to break down the neon lamp. $C1$ keeps the direct current from $V3$ from flowing through the secondary S^2 of L^2 . A filter system consisting of $Z1$ and $C2$, similar to that used in ordinary battery eliminators has been inserted to change the pulsating current which comes through V^3 to direct current. When, however, a strong incoming signal is received, such as that caused by a crash of static or local disturbance, the impedance of V^3 will greatly decrease. This will cause a greater voltage to be impressed on $R2$ and $N2$. The resistance of $N2$ will then break down and become very small. Since in this instance the grid and filament are virtually shortcircuited the crash will not be recorded in the output circuit of $V2$.

It is obvious that a device similar to the one described in the preceding paragraph could be placed across the output circuit of the tube thereby shortcircuiting the plate and filament, with similar results. Also that the plate and grid of the tube could be shortcircuited by a similar device, placing the resistance and the neon lamp between these elements and inserting small condensers to keep the direct current from $V3$ off the plate and grid $V2$.

By referring to Fig. 3, we find that the principles illustrated above may be used to regulate the heat of the filament of the amplifier. Transformer $L3$ is across the A. C. current filament source of supply of the vacuum tube $V4$. In the output circuit of supplemental or auxiliary tube V^6 is inserted high resistance R^6 and neon tube N^4 and secondary S^3 of transformer L^3 . When the signal impressed on the circuit exceeds a predetermined limit the secondary S^3 of this transformer is virtually short-circuited through neon tube N^4 in accordance with principles described above, thus decreasing the inductance of the primary P^3 and decreasing the heat of the filament of V^4 . The resistances $R3$, preferably resistances with a positive temperature coefficient, have been inserted in the A. C. lines to cause the desired IR drop when the increased demands for current are made due to the decrease of impedance of the primary P^3 of L^3 .

The principles above described may be applied to circuits where the filament supply is direct current, by inserting the resistance in series with the filament supply current and varying the resistance of such elements, the IR drop across same, or both, in accordance with the principles already described.

It is further apparent that the general principles disclosed may be embodied in many organizations widely different from those illustrated without departing from the spirit of the invention as defined in the following claims.

It will be understood where vacuum tube amplifier is referred to in the claims it will include within its meaning thermionic tube amplifier or any equivalent tube amplifier.

The broad principle of my invention may be stated to be the method of automatic control of amplifying or rectifying, or other electrical circuits, consisting in rectifying or amplifying a portion of the input current and applying said rectified or amplified portion to an element in the secondary of a transformer, thereby varying the resistance of said element, thereby varying the impedance of the secondary of the transformer, thereby varying the impedance of the primary of said transformer, and thus controlling automatically the voltage drop across said primary.

What is claimed is:

1. In a vacuum tube amplifier set, a vacuum tube amplifier, a grid leak consisting of the primary of a transformer, an element in the secondary of said transformer which becomes highly conductive to electricity when a predetermined voltage is impressed thereon, and means for producing said predetermined voltage by rectifying a portion of the input energy of said set thereby virtually short-circuiting signal voltages above a predetermined valve from the grid to the filament of said tube.
2. In a vacuum tube amplifying system, means for discriminating against input energy above a predetermined value, said means comprising means for rectifying a portion of said input energy and for applying the rectified portion of said energy to a gas conducting tube, connected in the secondary of a transformer, to render the said gas conducting tube conductive, the primary of said transformer being connected as a grid leak of one of the vacuum tubes of said amplifying system.

In testimony whereof, I affix my signature.
